Primary Examiner — Gino Colan(74) *Attorney, Agent, or Firm* — Cook Alex Ltd.(57) **CLAIM**

We claim the ornamental design for a personnel lift vehicle, as shown and described.

DESCRIPTION

FIG. 1 is a right front perspective view of a personnel lift vehicle showing our new design;

FIG. 2 is a left front perspective view thereof;

FIG. 3 is a right rear perspective view thereof;

FIG. 4 is a left rear perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines shown in the figures are for the purpose of illustrating portions of the personnel lift device and form no part of the claimed design.

1 Claim, 10 Drawing Sheets(56)
